OR D 12,367

Fig. 1

Fig. 2.

UNITED STATES PATENT OFFICE.

AMASA LYON, OF NEW YORK, N. Y.

DESIGN FOR A PARASOL.

SPECIFICATION forming part of Design No. 12,367, dated July 19, 1881.

Application filed May 16, 1881. Term of patent 3½ years.

To all whom it may concern:

Be it known that I, AMASA LYON, a resident of New York, county of New York, and State of New York, have invented and produced a new and original Design for Parasols; and I do hereby declare that the following is a full, clear, and exact description thereof, reference being had to the accompanying drawings, and to the letters of reference marked thereon, making a part of this specification.

My invention relates to a new and original design for parasols.

The leading feature of my design consists in an ornamental border for the edge of the parasol, which, when the parasol is closed and the folds of the cover wrapped around the stick and secured by a ring at its upper end, will form a whirl, made up of a series of involute curves, each of which is produced by the edges of the border included between the terminal points of the ribs of the parasol.

Figure 1 is an elevation of my newly-designed parasol opened, and Fig. 2 an elevation of the same when closed, these two views being deemed necessary to fully illustrate my design.

A is the cover, B the lining, and C the stick or handle of the parasol. D D are the terminals or tips of its ribs.

E is a bordering-strip secured to the edge of the cover. This strip is formed in plaits or narrow flat folds, presenting to the eye a se-

ries of regular angular transverse indentations, substantially as represented in the several figures. When the parasol is closed and the folds of the cover are wrapped upon and about the frame, and confined by a ring, F, slipped over it, as shown in Fig. 2, the folds of the bordering - strip E drop away from the points of the ribs, and by reason of the plaits therei produce involute indented curves S S in a whirl between the ring F and the projecting stick or handle C. The indented edges of these curves S S, in combination with the indented intervals between them, present to the eye a very rich and ornamental effect, which is heightened and made very beautiful by lining the parasol - border with a color in brilliant contrast with that of the cover.

What I claim as new, and desire to secure by Letters Patent, is—

The design for a parasol, the same consisting of a plaited strip upon the edge of the cover, forming a whirl of involute indented curves S S between the ring and the handle of the closed parasol, substantially as herein shown and described.

In testimony whereof I have signed my name to this specification in the presence of two subscribing witnesses.

AMASA LYON.
